(57) **CLAIM**

The ornamental design for a controller for drone as shown and described.

DESCRIPTION

FIG. 1 is a perspective view of a controller for drone showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines immediately adjacent to the shaded surfaces depict the bounds of the claimed design, whereas all other broken lines depict portions of the controller for drone that form no part of the claimed design.
